CLAIM

We claim the ornamental design for a chair, as shown and described.

DESCRIPTION

FIG. 1 is a top upper perspective view of a chair;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof;

FIG. 7 is a left side elevation view thereof; and,

FIG. 8 is a rear lower perspective view thereof.

The ornamental design which is claimed is shown in solid lines in the drawings.

The broken lines shown in the drawing are for the purpose of illustrating environmental structure and form no part of the claimed design.
